UNITED STATES PATENT OFFICE

JESSE G. KING, OF DAYTON, OHIO, ASSIGNOR, BY MESNE ASSIGNMENTS, TO FRIGIDAIRE CORPORATION, A CORPORATION OF DELAWARE

REFRIGERATING APPARATUS

Application filed September 30, 1927. Serial No. 223,076.

This invention relates to refrigerating apparatus particularly to the form of refrigerating element and its arrangement in household refrigerator cabinets.

6 One of the objects of the invention is to provide an improved and simplified form of evaporator which is effective to cool circulating air in a cabinet and to freeze ice for table use, and which may be placed within a confined space.

Another object of the invention is to improve and simplify the arrangement and construction of evaporators to reduce their cost of manufacture.

15 Further objects and advantages of the present invention will be apparent from the following description, reference being had to the accompanying drawings, wherein a preferred form of the present invention is clearly shown.

In the drawings

Fig. 1 is a front elevation of a refrigerator cabinet having the improved refrigerating element therein;

25 Fig. 2 is a vertical section through the cabinet showing the refrigerating element in elevation; and

Fig. 3 is a plan view of the refrigerating element as viewed from below.

30 Evaporators for the dual purpose of chilling circulating air to cool a refrigerating cabinet and for freezing ice for table use have heretofore been constructed in accordance with my Patent No. 1,654,504 patented Dec.

35 27, 1927, and usually include a header which forms a reservoir for liquid refrigerant and a number of loops of tubing depending from the header for circulating refrigerant. These loops are arranged to enclose a freezing space,

40 in which are placed shallow pans for freezing ice for table use, and also to extend outwardly beyond the freezing space to chill circulating air for cooling the cabinet. The freezing space has been comparatively sheltered from circulating air, one set of tubes being provided principally for ice freezing, and

45 another set for the principal purpose of cooling the circulating air. These evaporators have usually been placed in a corner of the cabinet and leave an L-shaped storage com-

partment for food as shown in the application of Harry B. Hull, filed May 30, 1923, Serial No. 642,369. While this arrangement is very effective, the refrigerating element occupies a rather large amount of space. In 55 the case of small cabinets, for instance for apartment house use, the provision of considerable space for food storage is very important. This reduces to a small amount the space available for the refrigerating element 60 in the cabinet. If refrigerating elements of the form previously described are used the legs of the L-shaped storage compartment may be so narrow or short as to be practically useless. Moreover, it is wasteful of space to 65 devote one set of tubes to freezing ice and another set to the cooling of circulating air.

In accordance with my invention I provide an evaporator which is very compact and flat, and which may be disposed entirely 70 across the top of a cabinet thus leaving a substantially cubical space for the storage of food. I also construct the evaporator so that the ice freezing and air cooling elements are combined and space is thus conserved. 75

Referring to the drawings, particularly Fig. 2, my evaporator includes an elongated and preferably cylindrical header 10 which forms a reservoir for liquid refrigerant, and a plurality of conduit means for circulating 80 refrigerant which extend laterally beside the header. Preferably each conduit means is in the form of a serpentine tube 11 connected at each end to the header below the liquid level, and lying in a horizontal plane which 85 is substantially tangent to the bottom of the header. Preferably two such conduits are used, one on each side of the header. On top of, and preferably soldered to the serpentine tube, is a sleeve or pocket 12 forming a compartment for an ice-making container 13. The tube 11 extends back and forth across substantially the entire bottom surface of the compartment. The compartment is preferably of such dimensions as to lie within the 95 height of the header.

The evaporator is supported in the top of the cabinet in any suitable manner (as by straps 14 bolted to the top wall of the cabinet) and is placed as near to the top wall as frost. 100

ing conditions will permit. It will be understood that during operation the evaporator becomes coated with frost, and sufficient space must be left around the evaporator for this frost to form without touching the walls of the cabinet, for if it were permitted to touch the walls this would increase the heat leakage into the cabinet and cause the walls to sweat. Accordingly a space 15 indicated in Fig. 2 is left between the header and the top of the cabinet.

Surrounding the evaporator within the cabinet is a U-shaped partition 20 which separates the cabinet into a cooling compartment 21 and a storage compartment 22. This partition extends substantially across the entire width of the cabinet leaving only air circulating flues 23 on either side. Openings 24 admit warm air from the cabinet to the cooling compartment and an opening 25 admits cold air from the cooling compartment to the storage compartment. Preferably the bottom wall of the partition is provided with a drip pan 26 and a baffle 27 for the opening, the drip pan being separated from the partition by an insulating air space 28 as more fully described in the patent of George F. Hofferberth, No. 1,768,598 patented July 1, 1930. The front of the cooling compartment is preferably closed by a wall 29 which has openings to admit the ice-making containers 13.

The air circulates as shown by the arrows in Fig. 2, upwardly through the flues 23 and downwardly over the enclosures for the ice-making containers, thence under the tubes 11 and out through the opening 25. In this manner the tubes 11 serve two purposes, namely, cooling the compartments for the ice-making receptacles and cooling the circulating air which flows under and in contact with them. It will be noted, however, that the enclosures themselves form large surfaces projecting into the path of the circulating air. Consequently these compartments also serve to cool the circulating air.

If space requirements permit I prefer to attach a vertical serpentine fin 31 to each of the serpentine coils 11. This fin extends downwardly any desired distance from the coil and assists in cooling air circulating under the coil.

It will be observed that the evaporator above described effectively cools circulating air and that it is provided with considerable ice capacity. Nevertheless the entire evaporator may be contained within the height of the header and consequently permit the installation of the evaporator in a very thin space. This is a decided advantage in the case of small cabinets as it increases the space available for the storage of food and permits the construction of a food compartment of a convenient and economical shape. While the form of embodiment of the invention as herein disclosed, constitutes a pre-

ferred form, it is to be understood that other forms might be adopted, all coming within the scope of the claims which follow.

What is claimed is as follows:

1. An evaporator for refrigerating apparatus including a header forming a reservoir for liquid refrigerant, a serpentine tube connected at its ends to the header below the liquid level thereof and disposed in a substantially horizontal plane at one side of the header, and a compartment for an ice-making container supported on the upper side of the tube. 70

2. An evaporator for refrigerating apparatus including a header forming a reservoir for liquid refrigerant, a serpentine tube connected at its ends to the header below the liquid level thereof and disposed in a substantially horizontal plane at one side of the header, a compartment for an ice-making container supported on the upper side of the tube, and a vertical serpentine fin attached to the tube and extending below it. 80

3. Refrigerating apparatus including a cabinet; a partition dividing the cabinet into a cooling compartment and a storage compartment, the cooling compartment occupying substantially the entire width of the cabinet; and a shallow flat refrigerating element extending substantially the entire width of the cooling compartment and including a header forming a reservoir for liquid refrigerant, conduit means for circulating refrigerant extending substantially horizontally from the header, and a compartment for an ice-making receptacle supported on and above the conduit means and projecting into the path of air circulating through the cooling compartment. 90

4. An evaporator for refrigerating apparatus including a header forming a reservoir for liquid refrigerant, a tube connected at its ends to the header below the liquid level thereof and disposed in a substantially horizontal plane at one side of the header, and a compartment for an ice-making container supported on the upper side of the tube. 100

5. An evaporator for refrigerating apparatus including a header forming a reservoir for liquid refrigerant, a conduit means connected to the header and disposed entirely below the liquid level thereof and in a substantially horizontal plane at one side of the header, and a compartment for an ice-making container supported on the upper side of the tube. 110

In testimony whereof I hereto affix my signature.

JESSE G. KING.
